REFRIGERATING APPARATUS OF THE COM-
PRESSION TYPE

Rudolf Hintze, Berlin-Charlottenburg, Germany,
assignor to Siemens-Schuckertwerke Aktien-
gesellschaft, Berlin-Siemensstadt, Germany, a
corporation of Germany

Application February 24, 1938, Serial No. 192,287
In Germany February 26, 1937

13 Claims. (Cl. 230—79)

This invention relates to improvements in compressor units, in particular for refrigerating apparatus.

In the manufacture of inexpensive yet highly economical refrigerating apparatus, especially for domestic purposes, it appears favorable to employ compressors of simple and reliable construction, the parts of which require as little machining as possible. Various suggestions thus have been made for simplifying the manufacture of refrigerator compressors without impairing their reliable and economical operation. However, the fact that a great number of parts constituting the known compressors must be very accurately machined to gauge, which implies a considerable increase in the cost of production, hitherto has kept the prices of refrigerators on a relatively high level, although a refrigerator placed on the market at more moderate cost would answer a perennial and extensive demand.

An object of my invention is to provide a refrigerating apparatus of the compression type in which the compressor has a simple, economical and reliable construction which allows simplifying the manufacture and reducing the cost of manufacture as compared with the compressors heretofore employed in refrigerating apparatus.

Another object of the invention is to reduce in a compressor of the type here concerned those elements which in order to ensure a satisfactory operation require an accurate machining to gauge.

Still another object is to combine an electric motor and a rotary compressor in such a way that the compressor when in operation also produces an effective lubrication of the motor.

An object also is to produce the compressive effect by means of a liquid pumping medium which at the same time is used as a lubricant.

A further object of my invention is to construct a compressor unit, in particular for refrigerating systems, which while employing a liquid pumping medium ensures by simple and effective means a separation of this liquid from the fluid to be compressed.

An object also is to provide for the starting of the electro-motor of a refrigerating system under no load condition without using additional pressure relief valves or similar auxiliary mechanisms.

Further objects concern a favorable structural combination of a separate lubrication pump with a compressor unit, in particular, with a rotary element of a so-called liquid-ring compressor, and

other improvements as will become apparent from the following.

According to the invention, a self-priming centrifugal pump utilizing the action of a revolving liquid ring is made use of for drawing in the refrigerant from the evaporator and for compressing the same. The individual parts of such a compressor, hereinafter referred to as liquid-ring compressor, need not in the course of manufacture be accurately machined to gauge. The compressor further presents the great advantage that it ensures a starting under no load of its driving motor without the necessity of employing auxiliary control means. For this reason the liquid-ring compressor may be attached directly to the driving motor. In practice the driving motor is preferably connected directly to the vane wheel of the liquid ring compressor and the container in which the liquid ring operates is rotatably mounted so that it is entrained by the vane wheel owing to the friction of the liquid. Further features of the invention will become apparent from the following description of the embodiments illustrated in the drawings.

Fig. 1 is a vertical sectional view of a motor-compressor set according to the invention enclosed in a housing which is under pressure of evaporation. Fig. 2 shows a horizontal sectional view of the liquid-ring compressor of Fig. 1. Fig. 3 is a vertical sectional view of a modified form of the invention in which the housing containing the motor-compressor set is under pressure of condensation. Fig. 4 shows another modification of the invention in which the liquid ring compressor has only one chamber. Fig. 5 is a horizontal sectional view of the liquid ring compressor of Fig. 4. Fig. 6 shows a domestic refrigerator in diagrammatic form equipped with the compressor shown in Figs. 4 and 5.

Referring to Fig. 1, 1 denotes the stationary housing of the compressor. The upper part of the housing contains the electric motor, the compressor being arranged in the lower part. The bottom portion of housing 1 forms an oil sump. The stator 2 of the electric motor is mounted in a support 3 which separates the chamber 4 for the reception of the compressor from the upper part containing the electric motor. The rotor 5 of the electric motor is mounted on a shaft 6 arranged in the support 3. To the lower end of the shaft is secured the impeller 24 of the liquid-ring compressor having the shape of a vane wheel.

In Fig. 2 is shown a cross-section of the container and of the vane wheel, in which 8 de-

notes the container for the liquid ring. The container 8 is rotatably mounted on the shaft 9 firmly secured to the bottom 10 of the housing 1 and is provided with a hub 11 in which are arranged passages 12. The vane wheel 24 has eight compartments 13 or pumping chambers from which extend channels 14 in the upward direction. When the compressor is in operation these channels 14 cooperate with a suction duct 15 and a pressure duct 16 respectively, arranged in the lower part of the supporting member. 17 denotes a check valve inserted in the pressure duct for controlling the flow of the refrigerant. Conduits 18, 19 and 20 join the liquid-ring compressor with a condenser 21, a control valve 22 and an evaporator 23 so as to form a refrigerating circulation system.

When the apparatus is at rest the housing 1 is filled up with oil to the level h_1 . When starting the electric motor the pumping chambers 13 of the vane wheel 24 are not yet closed by the liquid ring but are at first all in open communication with the suction conduit 18 of the refrigerating system. Consequently, the motor may start under no load. Owing to the rotation, the liquid contained in the housing 8 is whirled outward by the centrifugal force and fresh liquid is continuously forced in the upward direction through the passages 12. This is continued until the liquid ring closes the chambers 13 completely, whereupon the motor is under full load. The rotating liquid ring now has the shape indicated in Figs. 1 and 2 by 25, its inner surface being designated by 26. The refrigerant drawn into the chamber 4 through the conduit 18 now passes through the conduit 19 and the channel 15 into that chamber 13 of the vane wheel, the channel 14 of which just passes the channel 15 and temporarily communicates with the channel 15. This chamber 13 is that shown in position I at the right-hand side of Fig. 2. Upon rotation through an angle of 180° , this chamber, while cutting off the communication of its passage 14 with channel 15, passes through positions II, III and IV into position V wherein passage 14 communicates with conduit 20 through check valve 17. Owing to the eccentricity of liquid ring 25 with respect to wheel 24, the refrigerant enclosed in chamber 13, when it leaves position I, is increasingly compressed until position V is reached and the compressed refrigerant is forced through the channel 14 and the check valve 17 into the pressure conduit 20. Chamber 13, while passing from position V through positions VI, VII, VIII and IX, is subjected by the liquid ring to an increasing suction, so that as soon as position I is reached or approached and the chamber again communicates with channel 15, another amount of refrigerant is drawn in. The eight other chambers 13 act accordingly.

The compressed refrigerant forced through valve 17 passes into the condenser 21 and, when liquefied, through control valve 22 into the evaporator 23 whence it is drawn into the chamber 4 of the compressor through the suction conduit 18. During the operation of the compressor, the oil in the bottom portion of the housing is intensively agitated by the rotary container 8 so that an effective lubrication is obtained.

Fig. 3 shows another embodiment of the invention in which the compressor housing is under pressure of condensation, the parts corresponding to those shown in Fig. 1 being denoted by the same reference numerals. In this embodiment

the suction conduit 18 extending from the evaporator is directly connected to the suction channel 15 arranged in the supporting member 3.

The liquefied refrigerant is supplied in this case to the housing 1 of the compressor through the pressure duct 16 and the check valve 17 so that the housing is under pressure of condensation. The conduit 20 leading to the condenser 21 is connected to the housing 1. Here the housing 1 acts as an oil separator, since the vaporous refrigerant containing oil forced out through the pressure channel 16 will be separated from the oil when impinged upon the wall of the housing. The oil flows along the walls of the casing 1 in the downward direction, whereas the vapors flow into the condenser through the conduit 20. Dichlormethane or other refrigerants having a low pressure of condensation may be employed as refrigerants in the refrigerating apparatus according to the invention. Under certain circumstances, also a multi-stage arrangement of liquid ring compressors may also be employed.

The motor-compressor set in Figs. 4 to 6 is enclosed in a housing consisting of a pot-shaped tank 31 and a cover 32. To the cover is secured the stator 33 of the electric motor by means of its support 34. The rotor 35 of the electric motor is mounted on a hollow shaft 36 rotatably mounted in an upper bearing 37 secured to the cover 32, and in a lower bearing 38 forming part of the support 34. The lower part 39 of the hollow shaft carries the impeller 40 of the liquid-ring compressor. To the impeller 40 are secured two plates 42, 43 by means of rivets 41. 45 denotes the container in which is set up the liquid ring upon the rotation of rotor 40. The container 45 is rotatably mounted on a bearing 46 secured to the support 34 of the stator by means of arms 47. The bearing 46 has a stationary pinion 48 in the form of a hollow shaft and is designed as an oil pump according to my copending application, Serial No. 160,011, filed August 20, 1937.

The oil filling the lower portion of the housing 31 passes during the operation through the inlet channels 49, the thread 50 of the oil pump and the channels 51 into the inner bore 52 of the stationary part of the pump and then into the conduit 53 which extends through the upper cover 32 of the housing 31 as indicated at 54. The lubricant is forced through a cooler 55 arranged exteriorly of the housing 31 and then passes into the lubrication channels 56, 57 of the hollow shaft 36 and returns to the lower part of the housing 31 through outlet openings 58.

At standstill the housing 31 is filled with oil up to the level h_1 . When starting the electric motor the liquid-ring container 45 is entrained by the rotation of the impeller 40 so that the oil may enter the container 45 through the lower inlet openings 59. In operation the oil is adjusted owing to the centrifugal force that it fills up the portion of the liquid container 45 as indicated at the right-hand side of the container. The oil level in the housing 31 then attains the height h_2 . The liquid ring is supplied with fresh oil through the openings 59 owing to the pumping action brought about during the rotation of the container. The excessive oil flows back into the housing 31 through the upper opening 61.

The suction and pressure effect is produced in operation by the extension 44 connected to the impeller 40 and cooperating with the liquid ring in the container 45. The refrigerant is drawn in from the evaporator through the conduit 62 and passes through the hollow shaft 36 into the duct

63 extending through the impeller (Fig. 5) and then into the suction chamber formed of the liquid ring, the two plates 42, 43 and the rotor 40, whence it is forced through a pressure valve 64 into the pressure duct 65 which communicates with the inner space of the housing 31. The compressed refrigerant passes then from the interior of the housing to the condenser through a conduit 66 connected to the cover 32.

In the embodiment shown in Fig. 6, the housing 31 of the motor-compressor set is mounted on top of the refrigerator cabinet and is supported by springs 67. 68 denotes the evaporator of the refrigerating apparatus. 69 is an air-cooled condenser from which the liquefied refrigerant is supplied through a conduit 70 to a container 71 in which operates a float-controlled valve 72. From the container 71 the liquid is supplied to the evaporator through a conduit 73. 74 and 75 denote the oil circulation conduits extending to the air cooler 55 for the lubricant. The set is cooled by a fan 77 driven by an electric motor 76. This fan supplies cooling air in the direction of the arrow for dissipating the heat of the condenser and the cooler 55. The cooling air enters the hood 79 enclosing the apparatus through an opening 78 in the rear of the refrigerator and escapes through front outlets 80.

The oil contained in the apparatus as shown in the embodiment according to Figs. 4 to 6 serves various purposes. First, it forms the liquid ring necessary for the operation of the compressor, secondly it lubricates all rotating parts and bearings, and finally its circulation is utilized for dissipating to the atmosphere the heat developed in the compressor and the electric motor. In a number of applications, the last-mentioned function is effected satisfactorily also if the fan shown in Fig. 6 is dispensed with.

The apparatus shown in Figs. 1 and 3 is preferably so designed that it may be mounted in a domestic refrigerator in a manner similar to that shown in Fig. 6.

What is claimed is:

1. A compressor unit, in particular for refrigerating systems, having a sealed housing forming an oil sump, a limited quantity of oil disposed in said sump, a stationary member in said housing having a suction duct and a compression duct, a rotary impeller arranged in said housing, a container eccentrically surrounding said impeller and forming a pumping chamber together with said impeller, said suction duct and said compression duct being arranged to sequentially communicate with said chamber when said impeller is in operation, said container having ducts communicating with said sump to effect the formation of an annular oil body in said container for compressively acting on said chamber when said impeller is in operation, an electric motor disposed in said housing and connected with said impeller, and means for causing the oil to lubricate said motor when said impeller is in operation.

2. A compressor unit for refrigerating apparatus, having a sealed housing forming an oil sump, a limited quantity of oil disposed in said sump, a stationary member in said housing having a suction duct and a compression duct, said suction duct communicating with the interior of said housing, a rotary impeller arranged in said housing, an annular container eccentrically surrounding said impeller and forming a pumping chamber together with said impeller, said suc-

tion duct and said compression duct being arranged to sequentially communicate with said chamber when said impeller is in operation, said container having ducts communicating with said sump to effect the formation of an annular oil body in said container for compressively acting on said chamber when said impeller is in operation, an electric motor disposed in said housing and connected with said impeller, a pressure conduit connected with said pressure duct and leading directly out of said housing, a suction conduit connected with said housing, said suction duct opening into said housing so as to maintain said housing under the low suction pressure, and means associated with one of the aforesaid movable parts of the compressor unit for causing oil from said sump to lubricate said motor when said impeller is in operation.

3. A compressor unit for refrigerating apparatus, having a sealed housing forming an oil sump, a limited quantity of oil disposed in said sump, a stationary member in said housing having a suction duct and a compression duct, said compression duct having its discharge end communicating with the interior of said housing, a rotary impeller arranged in said housing, a container eccentrically surrounding said impeller and forming a pumping chamber together with said impeller, said suction duct and said compression duct being arranged to sequentially communicate with said chamber when said impeller is in operation, said container having ducts communicating with said sump to effect the formation of an annular oil body in said container for compressively acting on said chamber when said impeller is in operation, an electric motor disposed in said housing and connected with said impeller, means associated with one of the aforesaid movable parts of the compressor unit for causing oil from said sump to lubricate said motor when said impeller is in operation.

4. A compressor unit for refrigerating apparatus, having a sealed housing forming a sump, a limited quantity of pumping liquid disposed in said sump, a stationary member in said housing having a suction duct and a compression duct, said compression duct having its discharge end communicating with the interior of said housing, a rotary impeller arranged in said housing, a container eccentrically surrounding said impeller and forming a pumping chamber together with said impeller, said suction duct and said compression duct being arranged to sequentially communicate with said chamber when said impeller is in operation, said container having ducts and communicating with said sump to effect the formation of a centrifugated liquid ring in said container compressively acting on said chamber when said impeller is in operation, a suction conduit connected with said suction duct and leading directly out of said housing, and a pressure conduit communicating with the interior of said housing and having its opening above said liquid medium.

5. A compressor unit for a refrigerating circulation system, having a sealed housing forming an oil sump, a limited quantity of oil disposed in said sump, a stationary member in said housing having a suction duct and a compression duct, said suction duct communicating with the

interior of said housing, a rotary impeller arranged in said housing, a rotatable container eccentrically surrounding said impeller and forming a pumping chamber together with said impeller, said suction duct and said compression duct being arranged to sequentially communicate with said chamber when said impeller is in operation, said container having ducts communicating with said sump to effect the formation of an annular oil body in said container for compressively acting on said chamber when said impeller is in operation, an electric motor disposed in said housing and connected with said impeller, means associated with one of the aforesaid movable parts of the compressor unit for causing oil from said sump to lubricate said motor, a pressure conduit connected with said compression duct and leading out of said housing, and a suction conduit connected with said housing so as to maintain the interior of said housing under low pressure.

6. A motor-compressor unit for refrigerating systems, comprising a sealed housing forming an oil sump, a limited quantity of oil disposed in said sump, an electric motor having a vertical shaft and being disposed in the upper portion of said housing, and a compressor disposed in the lower portion of said housing, said compressor including a stationary member having a suction duct and a compression duct, said compression duct communicating with the interior of said housing, a check valve arranged between said compression duct and the interior of said housing, an impeller firmly mounted on said shaft and an independently rotatable container eccentrically surrounding said impeller and forming a pumping chamber together with said impeller, said suction duct and said compression duct being arranged to sequentially communicate with said chamber when said impeller is in operation, said container having ducts communicating with said sump to effect the formation of an oil ring compressively acting on said chamber when said impeller is in operation.

7. A motor-compressor unit, in particular for refrigerating apparatus, comprising a sealed housing forming an oil sump, a limited quantity of oil disposed in said sump, an electric motor having a vertical shaft and being disposed in the upper portion of said housing, and a compressor disposed in the lower portion of said housing, said compressor including a stationary member having a suction duct and a compression duct, an impeller mounted on said shaft, and a rotary container eccentrically surrounding said impeller so as to form a pumping chamber together with said impeller, said suction duct and said compression duct being arranged to sequentially communicate with said chamber when said impeller is in operation, said container having ducts communicating with said sump to effect the formation of an oil ring compressively acting on said chamber when said impeller is in operation, and means for pumping oil from said lower portion into said upper portion of said housing for lubricating said motor, said means being operatively connected with said compressor.

8. A motor-compressor unit, in particular for refrigerating apparatus, comprising a sealed housing forming an oil sump, a limited quantity of oil disposed in said sump, an electric motor having a vertical shaft and being disposed in the upper portion of said housing, and a compressor disposed in the lower portion of said housing, said compressor including a stationary member

having a suction duct and a compression duct, an impeller mounted on said shaft, and a rotary container eccentrically surrounding said impeller so as to form a pumping chamber together with said impeller, said suction duct and said compression duct being arranged to sequentially communicate with said chamber when said impeller is in operation, said container having ducts communicating with said sump to effect the formation of an oil ring compressively acting on said chamber when said impeller is in operation, a rotary lubrication pump arranged in said housing below said compressor, said pump having two cooperating pumping members, one of said members being stationary, said other member being connected with said rotary container, and a conduit system connecting said pump with the places to be lubricated in said upper portion of said housing.

20 9. A motor-compressor unit of the class described, comprising a pressure-tight housing forming a sump, a limited quantity of pumping liquid disposed in said sump, an electric motor arranged in said housing and having a hollow shaft, an impeller mounted on said shaft, a rotatable container eccentrically surrounding said impeller and forming a pumping chamber together with said impeller, said container having duct means communicating with said sump to allow, when said impeller is in operation, the formation of an annular body of said liquid for alternately producing suction and compression in said chamber, said impeller having a duct for connecting said chamber with the hollow of said shaft and another duct for connecting said chamber with the interior of said housing, said ducts being arranged to sequentially communicate with said hollow and the interior of said housing during the rotation of said impeller, and 40 two conduits for conveying the fluid to be compressed, one of said conduits being connected with the hollow of said shaft, and said other conduit being connected with the interior of said housing.

45 10. A motor-compressor unit of the class described, comprising a pressure-tight housing forming a sump, a limited quantity of pumping liquid disposed in said sump, an electric motor arranged in said housing and having a hollow shaft, an impeller mounted on said shaft and having a peripheral recess, a container eccentrically surrounding said impeller and forming a pumping chamber together with said impeller, said impeller having a projection limiting the 55 peripheral length of said recess, a duct connecting one peripheral end of said recess with said hollow shaft, and a second duct opening into the other end of said recess, said container having a passage connecting its interior with 60 said sump to allow, when said impeller is in operation, the formation of an annular body of said pumping liquid for compressively acting on said chamber, two conduits for conveying the fluid to be compressed, one of said conduits being connected with the hollow of said shaft, the other conduit being in communication with said second duct, and a check valve associated with 65 said unit so as to control one of said ducts.

70 11. A motor-compressor unit of the class described, comprising a pressure-tight housing forming a sump, a limited quantity of pumping liquid disposed in said sump, an electric motor arranged in said housing and having a hollow shaft, an impeller mounted on said shaft and having a peripheral recess, a projection limiting

the peripheral length of said recess, a suction duct connecting one peripheral end of said recess with said hollow shaft, and a pressure duct connecting the other end of said recess with the interior of said housing, a check valve arranged on said impeller for controlling said pressure duct, a container eccentrically surrounding said impeller and forming a pumping chamber together with the recessed peripheral portion of said impeller, said container having duct means 10 communicating with said sump to allow, when said impeller is in operation, the formation of an annular body of said liquid for alternately producing suction and compression in said chamber, a suction conduit connected with the hollow 15 shaft, and a pressure conduit connected with said housing.

12. A motor-compressor unit of the class described, comprising a pressure-tight housing forming an oil sump, a limited quantity of oil disposed in said sump, a rigid support disposed in said housing, an electric motor mounted on said support, an impeller of a liquid-ring pump connected with said motor, a rotary container eccentrically surrounding said impeller and communicating with said sump to allow said oil to form a ring in said container when impelled by said impeller, a lubrication pump having a rotary pumping member associated with said container, and a stationary pumping member 30 mounted on said support, stationary conduit means connecting said pump with said motor for supplying oil directly from said sump to the parts to be lubricated of said motor, and two conduits communicating with the interior of said 35

liquid-ring pump and the interior of said housing, respectively, for conveying to and from said unit the fluid to be compressed.

13. A motor-compressor unit, in particular for refrigerating apparatus, comprising a sealed housing forming an oil sump, a limited quantity of oil disposed in said sump, an electric motor having a vertical shaft and being disposed in the upper portion of said housing, and a compressor having a stationary member having a suction duct and a compression duct and being disposed in the lower portion of said housing, said compressor including an impeller mounted on said shaft, and a rotary container eccentrically surrounding said impeller and forming a pumping chamber together with said impeller, said suction duct and said compression duct being arranged to sequentially communicate with said chamber, said container having oil passages communicating with said sump to permit, when in operation, part of said oil to enter into said container to allow the formation of an oil ring in said container compressively acting on said chamber, a rotary lubrication pump arranged in said housing below said compressor, said pump having two cooperating pumping members, one of said members being stationary, said other member being connected with said rotary container, an oil cooler arranged exteriorly of said housing, an oil conduit connecting said cooler with said pump, and another oil conduit connecting said cooler with the upper end of said vertical shaft.

RUDOLF HINTZE.
